UNITED STATES PATENT OFFICE

PAULINE WERNER, NÉE FRESENIUS, OF STUTTGART, GERMANY

BUST SUPPORT

Application filed September 21, 1927, Serial No. 220,980, and in Germany November 2, 1926.

My invention relates to bust supports and it is an object of my invention to provide a device of this type in which certain drawbacks of existing bust supports are eliminated, particularly with respect to the fitting in the region of the breast bone.

To this end, I provide a bust support having a pair of holders or pockets, a belt below the pockets, the usual shoulder straps, and a cross brace intermediate the pockets, which holds them down to the breast bone.

Bust supports as heretofore designed do not fulfill all requirements. Some do not fit the body properly; some show under the dress, some are uncomfortable, some become displaced while being worn, many exert undue pressure on the breasts, and many others do not fit properly in the region of the breast bone. It has been attempted to secure a proper fit at this point by stays or shoulder straps but this is not a satisfactory solution as such parts are objectionable from the hygienic point of view.

It has been proposed to overcome the aforesaid drawbacks by making a bust support from two independent holders or pockets, each of which is independently held in position by means of a waist band and a shoulder strap, but in this type the relative distance of the holders or pockets is indefinite and therefore the pockets will become displaced when the wearer is moving.

According to my invention, on the other hand, a bust support is provided the pockets of which fit properly in the region of the breast bone so that any ungainly hollowness is avoided, and which has an excellent, permanent and comfortable, all-round fit notwithstanding the motions of the wearer, and that without stays or other objectionable expedients. The parts of the support are permanently held in such relative position as to maintain the given shape of the figure, and to obtain a much better fit, particularly in the region of the breast bone, as compared with existing supports.

In the accompanying drawing, a bust support embodying my invention is illustrated diagrammatically by way of example.

Fig. 1 is a perspective front view,

Fig. 2 is a similar view showing another position of the wearer,

Fig. 3 is a rear view.

Referring now to the drawing, *a* are the holders or pockets, *b* are the shoulder straps, *c* are narrow rearward extensions of the pockets *a*, *d* are a pair of belt sections, preferably of resilient material attached to each extension *c*, *e* are fastening means, preferably hooks, at the end of each belt section *d*, and *f*, *f* are a pair of cross braces secured to the pockets *a* at their upper edges *g*, to which braces the hooks *e* of the belts *d* are attached.

As will appear from Figs. 1 and 3, the shoulder straps *b* are attached to the highest point of the pockets *a* at the front and to the extensions *c* at the rear so as to assume a substantially vertical position in which they have no tendency to slip.

The cross braces *f*, *f* which are preferably strong rubber bands, are attached to the pockets *a* near the central portion of their upper edges *g*. The braces cross at the central position of the support and have no fixed connection with each other nor with other parts of the support, except at *g*, and are preferably housed in the central portion, but without restraining them. The belt *d* from the left-hand pocket *a* is secured at *e* to that cross brace *f* which is attached to the right-hand pocket *a* at *g*, and vice versa. The connection at *e* is preferably detachable.

The cross braces *f* hold down the support at its central portion, and tightly fit it to the breast bone. The pull of the braces is transmitted to the points of attachment of the shoulder straps *b* substantially in the direction in which it is exerted, and the belts *d*, with the extensions *c* of the pockets, are so shaped that the upper edges of the pockets *a* which meet at an angle at the points where the straps *b* are attached, extend substantially in the direction of the components of the forces exerted by the pull in the straps *b*. Due to this arrangement, not only the lower belts *d* at the bases of the pockets will hug the body—as they do in any bust support—but the upper edges will do the same, and thus the support will fit firmly if it has been properly adapted to the body of the wearer.

With detachable fastenings at *e*, *e* the putting-on of the support does not involve any difficulty as the hooks, buttons or the like are in front and readily accessible. It is understood that the fastening may be varied without departing from my invention, for instance, instead of two hooks or the like, a single fastening might be provided for connecting the belts *d* at the centre in front or at the back, the cross braces *f* being in turn secured to their respective belts by any suitable detachable or permanent fastenings.

10 The belts *d*, with the extensions *c*, are of such small size that they will not show at the back with a décolleté dress.

15 Any suitable materials may be used for my bust supports, and, on account of its perfect fit, the pockets *a* may be made of unresilient material, for instance tulle.

20 I wish it to be understood that I do not desire to be limited to the exact details of construction shown and described, for obvious modifications will occur to a person skilled in the art.

25 I claim:

20 A bust support including a pair of breast pockets, each breast pocket having a cross brace attached at its upper end to the upper inner edge of one of said breast pockets and extending to the lower inner edge of the other breast pocket, and a belt section attached at one end to the lower outer corner of the pocket, the belt section of each pocket extending around the wearer under the other breast pocket and attached at its end to the lower end of the cross brace which is attached to the same pocket to which the other end of the belt section is attached.

In testimony whereof I affix my signature.
40 PAULINE WERNER, née FRESENIUS.
